UNITED STATES PATENT OFFICE.

BAGSTER ROADS SEABROOK, OF MISHAWAKA, INDIANA.

PHONOGRAPH SOUND BOX.

Application filed April 18, 1922. Serial No. 555,076.

My invention relates to improvements in phonograph sound boxes and it more especially consists of the features hereinafter pointed out in the annexed claims.

The purpose of my invention is to provide a sound box that shall more correctly translate the mechanical vibrations of a record into acoustic vibrations than is possible with sound boxes constructed in the ordinary manner; that has a specially shaped lining of a plastic self-hardening composition which is non-absorbent and non-responsive to the sound waves produced by the diaphragm; that also provides a special arrangement of diaphragm gaskets in order to insure a greater freedom and truthfulness of the diaphragm vibrations; and that also provides a specially shaped formed diaphragm.

With these and other ends in view, I illustrate in the accompanying drawing such instances of adaptation as will disclose the broad underlying features without limiting myself to the specific details shown thereon or described herein.

Fig. 1 is a side elevation of the sound box.
Fig. 2 is a front elevation of Fig. 1.

Fig. 3 is a side elevation in section of Fig.

1.
30 Fig. 4 is an enlarged elevation of the diaphragm gaskets and bearing rings.

Fig. 5 is an enlarged elevation of modified bearing rings.

In practically carrying out my invention, I may use sound box casing 1 provided with a flange 5 and secured to a tone arm terminal 3 by means of a flange 2. This terminal has an opening 4 which leads into the interior of the sound box. The flange 2 may be insulated from the sound box as shown. A retaining ring 11 is secured to the front of the sound box by means of screws 12 and it serves to hold the diaphragm in place.

The interior surface of the sound box is scored or roughened at 10 in order to assist in holding the composition 6 in engagement therewith. This composition is formed with an ogee curve 7, 8. The curve starts from the opening 4 and progresses into the rounded thickness 7 of convex form and then passes into the concave shape reducing the thickness of the composition 6 to its thinnest part at 8, and this concave portion terminates into a uniform thickness at 9 which thickness is somewhat less than that

of the convex portion 7. A metallic conically shaped bearing ring 16 may be imbedded in the composition 6 near its exterior as especially shown in Fig. 4. The ring 16 is placed in the composition while it is plastic 60 and by reason of its conical shape is held therein. It is assembled in any suitable manner to insure the apex 17 being concentric with the flange 5 of the sound box, and also parallel with the front face of this 65 flange. If desired, the ring 16 may be formed as shown at 35 in Fig. 5, wherein it has an annular flanged projection 36. The flange 36 serves to hold the apex 17 concentric with the sound box within practical 70 limits.

The retaining ring 11 shown in enlarged relation in Fig. 4 has a shoulder 14 formed on its inner face. This shoulder coacts with the inside of flange 5 and serves to hold the 75 ring 11 concentric with the sound box casing. It is provided with an integral conical retaining ring 13 having its apex 15 directly opposite the apex 17 of the ring 16. In Fig. 3 the retaining ring is shown as 39 80 with an annular groove 40 between the conical portion 13 and the shoulder 14, while in Fig. 5 a retaining ring 33 is shown with a shoulder 37 against which a removable metallic conically shaped bearing ring 34 85 abuts.

The diaphragm is held between two flat rubber gaskets 18 having its exterior edge 19 removed from the inner face of the flange 5. This allows the diaphragm to 90 vibrate freely in the direction of the exaggerated diagonal lines 39 shown in Fig. 5 with its nodal point between the apex 15 and the apex 17 and in line with these. The diaphragm is formed curving as shown in 95 Fig. 3 with a very sharp short radius curve at 21 between the curved center and the straight rim 20 which is held between the gaskets 18. It is reinforced at its center by means of an interior washer 23 and the large 100 diameter exterior washer 22. These washers are very thin approximately the same in thickness as the diaphragm itself. The special features of the diaphragm as to its composition, etc., is not claimed herein but 105 is made the subject of separate prosecution.

The usual stylus bar 25 is secured to the diaphragm at 24 at one end and at the other end is attached to the enlarged portion 26 which serves as a needle carrier. It also has 110

a pivotal axis 27 that is held by conical ended screws 29 between the ears 28 that project from the sound box flange 25. The needle 32 is held in the opening 31 in the 5 usual manner by thumb screw 30.

When the composition 6 is given other shapes than that shown, the results are markedly different. In some cases producing squeaky and in other cases sharp metallic 10 tones which detract from the purity of the sound waves comprised in the record that is being played. The diaphragm may be made with more than one of the short radius curves 21. In any event, such 15 curves are found opposite the convex shape 8 of the composition. It is impossible to state from the standpoint of the physicist just what actually takes place between the diaphragm and the curved face of the composition 6, but as to the results there is no 20

question of their superiority over those produced by any other form of sound box hitherto known. In consequence of this superiority applicant claims a composition 25 lining to a sound box having a reverse curve face adjacent the diaphragm in its broadest aspect, as well as the solid metallic bearing rings in relation to the elastic gaskets.

What I claim is:

In sound boxes, a suitable flanged casing, and a composition lining therein having an opening therethrough, the lining being disposed in varying thicknesses greatest around the opening and thinnest between the opening and the periphery thereof and of intermediate thickness at the outer edge.

In testimony whereof I affix my signature.

BAGSTER ROADS SEABROOK.
